METHOD FOR REMOVING PAINT FROM
PAINTED ARTICLESJohn S. Judd, Birmingham, Mich., assignor to
Lyon, Incorporated, Detroit, Mich., a corpora-
tion of Michigan

Application November 10, 1948, Serial No. 59,385

2 Claims. (Cl. 134—30)

1

The present invention relates to a method for removing foreign deposits from coated objects, and more particularly to a continuous process for removing paint from painted objects.

The removal of paint from objects such as painting masks on a large industrial scale has always been expensive and time-consuming. When a large number of individual pieces are to be cleaned, it is highly impractical to scrub each individual piece with caustic in view of the time consumed in such an operation. When organic solvents are used, these solvents present a problem in fume disposal, since normal paint-removing solvents are somewhat noxious and cannot be tolerated in the atmosphere of the industrial plant.

An object of the present invention is to provide a method whereby individual painted objects may be freed of encrusted paint in a continuous system.

Another object of the present invention is to provide a method for removing paint from painted objects without permitting any substantial escape of noxious fumes from the paint-removing system.

A still further object of the present invention is to provide a method of removing paint from painted objects wherein the loss of the paint-removing solvent is minimized.

As a feature of the present invention, I provide a closed system for removing paint from painted surfaces wherein the object to be cleaned is first contacted with a paint-removing solvent in liquid form, and subsequently contacted with the same solvent in vaporous form.

Another feature of the present invention resides in the provision of liquid seals between the various stages of the process, thereby isolating the various stages and preventing the paint-removing solvent from circulating through the system and thereby interfering with heat transfer conditions.

In accordance with the present invention, the objects to be cleaned are passed through an inlet chamber, and thence through a liquid body of paint-removing solvent which forms a liquid seal between the inlet chamber and a succeeding spray section. Passage of the object through the first liquid body serves to wet the painted surface and loosen paint incrustations. After immersion in the liquid body, the object is passed into the spray section where it is contacted with a cold spray of solvent which serves to loosen or remove substantial quantities of the encrusted paint. After leaving the cold spray section, the object is passed

2

into a second pool of liquid paint-remover which serves as a liquid seal between the spray section on one side and a hot vapor section on the other. Passage of the object through the second body of liquid serves to remove substantially all of the paint which has been previously loosened and dissolved. After passage through the second liquid seal, the object is next contacted with hot vapors of the paint-removing solvent in a hot vapor zone. By contacting the object with hot vapors of solvent, evaporation of a substantial portion of the solvent clinging to the object is effected. After passage through the hot vapor section, the object is next passed through a cooling section where the object is cooled so that it may be handled easily, and any vapors carried from the hot vapor section are condensed and returned to the vapor zone.

In stripping paint from newly painted objects, it is important that the temperature of the object and of the paint be kept at a low value so that the paint does not set up on the mask. Once the paint is set up on the mask, the paint solvent will not remove it, and the object will have to be stripped in the conventional caustic tanks. In the present invention I have provided a method where the actual contacting with the paint solvent is carried out at controlled relatively cool temperatures. The object is heated to a substantial degree only in the hot vapor region, when the paint has already been substantially or completely removed.

As the solvent in the present process I prefer to use the trichloroethylene, although other solvent such as benzene, toluene, xylene, butyl diacetate and butyl lactate, or mixtures thereof, may also be used.

A further description of the present invention will be made in conjunction with the attached drawing which illustrates an apparatus adapted for carrying out the process of the present invention, and in which:

The figure is a schematic cross-sectional view of one embodiment of the present invention and illustrates four objects at various stages in the paint removal process.

As shown on the drawing:

Reference numeral 10 denotes in general a housing for the paint-removing assembly whose base portion is formed into an inclined wall 11, base portion 12, inclined walls 13, 14 and 15, base portion 16, upstanding walls 17 and 18 joined by cross member 19, base portion 20, and inclined wall 21.

Extending the full transverse width of housing

10 are a series of baffle plates including a slotted inlet baffle 22, a solid baffle 23, a slotted baffle 24, a solid baffle 25, and slotted baffles 26, 27, and 28. Extending the length of the housing 10 and supported therein is an arcuate track 29 which may 5 be formed into a generally sinusoidal configuration as shown in the figure. Track 29 supports a roller 30 mounted on an arm 31 which in turn supports the object or work piece 32 from which the paint is to be removed. Roller 30 is free to 10 move along track 29 through the various treating chambers as will be hereinafter described.

The figure shows the condition where four 15 separate work pieces are being treated in various stages of the paint-removing process. Commencing at the inlet end of the assembly, the work piece 32, supported by means of arm 31 which in turn is pivoted on roller 30, passes through a slot which is formed in the inlet baffle 22, permitting the passage of the supported work piece through the baffle with only a small clearance. After passage through baffle 22, the work 20 piece 32 is passed through an inlet chamber 33 which is defined by slotted baffle 22, sloping base wall 11, base portion 12, and solid baffle 23.

As shown on the drawing, the inlet baffle 22, the inclined wall 11, the base portion 12, and the inclined wall 13 define a container for a body 30 of relatively cool paint solvent 34. The work piece 32 is immersed into this body of paint solvent 34 and is next passed by means not shown into a spray chamber 35 which is defined by the surface of the liquid body 34, solid baffle 23, slotted baffle 24, and inclined base wall 14. It will be apparent that the liquid body 34 functions 35 as a liquid seal to prevent any vapors from chamber 35 passing back into inlet chamber 33.

Disposed within spray chamber 35 are a plurality of perforated pipes 36 which are fed by means of conduit 37, pump 38, and conduit 39 40 from the liquid body 34. The object to be cleaned, after immersion in the body 34, is passed in close proximity to the perforations of the perforated pipes 36, so that the work piece 32 is effectively sprayed with liquid paint solvent at the temperature approximating that maintained in liquid body 34.

A large portion of the spray is prevented from 50 running out of the spray chamber 35 by slotted baffle 24, and is conducted back into liquid body 34 by inclined base wall 14. After the spraying operation, the object is passed through the slotted baffle 24 and enters a second body of 55 relatively cool paint solvent 40 contained between sloping base wall 15, base portion 16, and upstanding wall 17. Disposed within the liquid body 40 are a series of cooling coils 41 which serve to maintain the liquid body 40 at a predetermined temperature below that at which substantial vaporization occurs. The liquid body 40 acts as a liquid seal between spray chamber 35 and a hot vapor chamber 42, thus minimizing the transfer of heat and vapor between the two 60 chambers.

The work piece 32 after immersion in the liquid body 40 is next passed through a slotted baffle 26 and into a hot vapor chamber 42 defined by the slotted baffle 26, a slotted baffle 27, and a body of relatively hot paint solvent 43. The heated liquid body 43 is contained between the 70 upstanding wall 18, base portion 20, and wall 45. Disposed within the heated liquid body 43 are a series of heating coils 44 which serve to impart a temperature to the liquid body 43 sufficient to vaporize a substantial part of the liquid body 75

thus maintaining a concentration of heated vapors in vapor chamber 42 sufficient to heat the object as it passes through the chamber 42. In the configuration shown in the drawing, heating coils 44 are insulated from cooling coils 41 by providing a dead air space 46 defined by walls 17, 18 and cross member 19 between the two sets of coils. In the vapor chamber 42, the work piece 32 is contacted with the heated vapors rising from the liquid body 43 which serve to heat the work piece 32 and evaporate a major portion of the solvent clinging to the work piece 32. After treatment in the vapor chamber 42, the work piece 32 is next passed through the slotted baffle 27 and diagonally through the space enclosed by a bank of condensing coils 47.

As shown on the drawing, the bank of cooling coils 47 is inclined slightly to the horizontal. The higher end of the bank of coils 47 is formed 20 to permit passage of the object 32 therethrough as by forming the bank 46 into a series of interconnected U-shaped tiers disposed on parallel planes. The object 32 thus enters the bank of condensing coils 47 near the base thereof and 25 passes upwardly through the space enclosed by the cooling coils and emerges over the lower rear end of the bank of condensing coils 47. The bank of cooling coils 47 serves the function of condensing any vapors occluded on the work piece 32 from the vapor chamber 42 as well as any extraneous vapors escaping from the vapor chamber 42. The condensed liquid is then returned to vapor chamber 42 by means of inclined base wall 21 through a suitable slot at 30 the base of the slotted baffle 21. The cooled object, after contact with the bank of cooling coils 46, is removed from the system through the slotted exit baffle 28 in a clean, dry, and relatively cool condition.

When trichloroethylene is used as the paint solvent, the liquid bodies 34 and 40 will normally be maintained at a temperature below 140° F. to prevent vaporization of the solvent. The heated liquid body 43 will be maintained at a temperature of about 180° F. in the case of trichloroethylene, or in any event, somewhat below the boiling point of the solvent used, so that substantial vaporization is effected in the vapor chamber 42.

It can thus be seen that I have provided a method and apparatus for removing paint from newly painted objects wherein the various treating steps are isolated by means of liquid seals, and have further provided a simple, efficient and continuous process for removing paint from 55 newly painted objects which may be carried out in a large scale operation.

While the above description has been concerned primarily with paint removal, it will be apparent that the method of apparatus can also be used for the removal of deposits such as tar and the like.

It is evident that many modifications may be made to the method disclosed herein, and it is not my intention to limit the invention to the single embodiment shown but limited merely as necessitated by the scope of the appended claims.

I claim as my invention:

1. The method of removing paint from a painted object which comprises immersing said object in a body of cold liquid paint solvent, spraying the object with cold liquid paint solvent in a spraying zone, passing the sprayed object into a second liquid body of cold paint solvent, passing the object from said second body into a va-

por zone, contacting said object with heated vapors of said solvent in said vapor zone to heat said object, and passing the heated object into a cooling zone to condense vapors from said vapor zone.

2. A process for removing paint from a painted object which comprises immersing said object in a bath of liquid trichloroethylene maintained at a temperature below 140° F., passing the object from said zone into a spray zone, 10 spraying the object in said spray zone with liquid trichloroethylene, immersing the sprayed object into a second body of liquid trichloroethylene maintained at a temperature below 140° F., passing the object from said second body into 15 a vapor zone, contacting said object with heated vapors of trichloroethylene in said vapor zone

to heat said object, and passing the heated object into a cooling zone to condense vapors from said vapor zone.
